POLISHED ROD ROTOR

Filed June 19, 1926

UNITED STATES PATENT OFFICE

ALEXANDER BOYNTON, OF SAN ANTONIO, TEXAS

POLISHED ROD ROTOR

Application filed June 19, 1926. Serial No. 117,195.

This invention relates to an attachment for well pumping equipment and more particularly to a polished rod rotor.

The invention forming the subject matter 5 of this application has for a principal aim the provision of simple means whereby a polished rod, the sucker rods, of course, and the cups of the working barrel may be turned slightly on the down strokes of the 10 pump to bring about uniform wear on the stuffing box, the working barrel, the cups, the polished rod, and the like, and at the same time to exert an intermittent tightening effort on the rods at the joints thereof 15 to avoid parting of the rods.

A further and equally important object is to provide a polished rod rotor which may be applied without disconnecting the polished rod from the beam, and without 20 altering the design of equipment already in use.

Another aim of the invention is to provide a polished rod rotor which may be easily arranged to permit of the pulling of 25 the rods without entirely detaching the rotor from the polished rod and the beam.

Other objects and advantages will be apparent during the course of the following description.

30 In the accompanying drawings forming a part of this application and in which like numerals are employed to designate like parts throughout the same,

Figure 1 is a side elevation of the rotor; 35 Figure 2 is a vertical section taken on line 2—2 of Figure 1;

Figure 3 is a group perspective of the body of the rotor.

In the drawing, wherein for the purpose 40 of illustration is shown a preferred embodiment of the invention, the numeral 5 designates a polished rod of conventional or other design, which, as shown in Figure 1, is extended through a polished rod trunnion 6 and has connection with the beam 7 whereby the rocking of the beam results in the reciprocation of the polished rod.

The improved rotor includes a substantially U-shaped saddle 8 having a centrally 45 arranged opening 9 for the reception of the

polished rod as is apparent. By reference to Figure 3 it will be seen that the sides or legs of the U-shaped saddle are provided with substantially semi-circular recesses 3 to partially receive the horizontal arms or 55 branches of the polished rod trunnion. As illustrated in Fig. 1, the trunnion 6 is mounted as indicated at 47 for a limited rocking movement on the beam.

It is thus seen that the saddle 8 is mounted on the trunnion and is capable of a limited movement thereon. The walls of the recesses 3 are provided in the upper portions thereof with shallow elongated notches or 60 sockets 10 to receive burs on the horizontal 65 branches of the trunnion 6, which burs are present on some trunnions due to parting of the molder's pattern. The provision of the shallow recesses 10 also enables the curved 70 walls of the recesses 3 to have uniform contact with the trunnion branches at opposite sides of the vertical center of the same to avoid lost motion. That is to say, the presence of the shallow recesses 10 permits of the limited 75 rocking of the saddle on the trunnion as a result of the conversion of the rocking movement of the beam into the reciprocation of the rods.

The saddle 8 constitutes a support for the 80 sleeve-like hub 12 of what might be said to be a ring-gear 14, the said ring-gear being positioned horizontally and having 85 constant mesh with a pinion 16.

In carrying out the invention, the pinion 16 is formed integral with a ratchet gear or 85 wheel 17 and these two power transmitting members define a combination gear mounted upon a stud 18. The stud 18 is carried by a bracket 20. Figure 3 illustrates that the bracket is provided with an attaching base 90 24 which may be formed integral with the saddle 8 and which is of annular formation to define a shallow recess to receive the lower portion of the sleeve-like hub 12 and a suitable lubricant.

A set screw 27 is threaded through the sleeve-like hub 12 and is adapted to engage the polished rod to lock the gear 14 to the polished rod. In this connection, it is noted 95 that suitable means may be employed to sup- 100

plement the locking action of the set screw 27.

The gear 17 is engaged by the teeth on a rack arm 30 pivoted as indicated at 31 to an actuator 33 in the nature of a vertical arm. Figure 1 illustrates that the forward portion of the rack 30 is provided with a depending flange 36 which moves between the gear 17 and a lug or extension 38 on the upper end of the bracket 20 to hold the rack 10 against lateral movement and in operative relation to the gear 17. In this connection, it will be noted that a coil spring 40 is connected to an apertured ear 41 of the rack 15 30 and to a lateral branch 43 of the actuator 33 and urges the teeth on the forward portion of the rack into constant engagement with the gear 17 as will be apparent.

Figure 1 illustrates that the actuator 33 20 is provided with an attaching base 50 having the ends thereof provided with flanges 51 adapted to extend on opposite sides of the beam. One of the flanges is provided with a set screw 54 by means of which a wedge 25 55 may be forced into pressure contact with an adjacent flange of the beam to hold the clamp or attaching member firmly in place.

When the improved rotator is to be installed the saddle 8 is first mounted on the 30 trunnion arms and the gear 14 is then slipped onto the polished rod so that the lower portion of the sleeve 12 will extend into the shallow recess within the member 24. With the gear thus positioned on the polished rod it will be in mesh with the pinion 16 and the rack 30 is now swung into engagement with the driven member 17, after which the spring 40 is connected to the ear 41 and the lateral branch 43 to urge 35 the teeth of the rack into constant engagement with the teeth of the driven member 17. Of course, the attaching member 50 is secured on the beam as suggested and to vary the extent of rotation of the rod on each down stroke of the pump the base may 40 be adjusted longitudinally on the beam.

More specifically, if the stroke of the beam is such that two or three teeth of the rack are engaged on each down stroke of 50 the pump and it is desired to engage say only one tooth, then by moving the rack forwardly toward the rotor assembly until only one tooth of the rack is engaged with a tooth of the gear 17 on the extreme up 55 stroke it is apparent that the intermittent rotation will be decreased. In this connection, it is noted that the depending guide flange 36 extends substantially to the rear of the teeth on the rack 30 so that the flange 60 will function even when the rack is adjusted to its foremost position.

As stated in the opening of this specification, one of the principal features of the invention resides in the fact that the rods may 65 be pulled without entirely dismantling or

disconnecting the improved rotator. Should it be desired to pull the rods, it is merely necessary to detach the spring 40 either from the ear 41 or the lateral branch 43 to permit the rack 30 to be swung on its pivot to an out-of-the-way position. With the rack 30 thus disengaged from the combination gear the polished rod may be removed without first disconnecting the sleeve-hub 70 12. Also the actuator 33 may be allowed to remain in place on the beam.

When the rods are again introduced into the well the rack 30 may be re-engaged with the combination gear as shown and the pumping renewed during which the rack 30 80 will actuate the combination gear on the down stroke of the rods. As the rods are rotated on the down stroke the friction and weight of the column of fluid on the rods on the up stroke of the rods is avoided. 85 However, there is sufficient friction between the cups or plunger and working barrel to bring about the intermittent tightening of all joints between working barrel and polished rod so that parting of the rods at the joints is overcome.

The weight of the rods, the cups or plunger and the column of fluid is transmitted through the hub 12 to the saddle 8 so there is considerable friction between the members 12 and 8. During the normal operation of the rotor the hub 12 will intermittently turn only in a clockwise direction on the saddle. During the back stroke of the actuator arm 30 there will be no tendency of the hub to partake of counter-clockwise movement.

However, should the cups or plunger stick in the working barrel a back strain will be built up in the rods and on the back stroke 105 of the actuator arm 30 the hub 12 will turn in a counter-clockwise direction to relieve this back strain. It will therefore be seen that the parts 12 and 8 constitute a friction clutch by which the rotor is prevented 110 from twisting the rods to the breaking point should the cups or plunger stick.

Having thus described the invention, what is claimed is:

1. A polished rod rotor comprising a substantially U-shaped saddle provided with sides having recesses to receive the lateral branches of a polished rod trunnion, the walls of said recesses being adapted to engage said branches at opposite sides of the vertical center of the branches, the upper portions of the walls of said recesses being provided with notches, a gear having a hub mounted on said saddle, and a rack to turn said gear.

2. A polished rod rotor comprising a gear having a hub provided with means whereby the same may be secured on a polished rod, a combination gear having teeth engaged with said first-named gear and being pro-

vided with ratchet teeth, a rack engaged with said ratchet teeth, a supporting member for said combination gear having an extension arranged in spaced relation to said combination gear, said rack being provided
5 with means extending between said combination gear and said extension whereby lateral movement of the rack is limited, and spring means urging said rack into engagement with the ratchet teeth of said combination gear.

10 3. A polished rod rotor comprising a gear having a hub provided with means whereby the same may be secured on a polished rod, a combination gear having teeth engaged
15 with said first-named gear and being provided with ratchet teeth, a rack extending across the top of and engaged with said ratchet teeth, a supporting member for said combination gear having an extension arranged in spaced relation to said combination gear, said rack being provided with means extending between said combination gear and said extension whereby lateral movement of the rack is limited, spring
20 means urging said rack into engagement with the ratchet teeth of said combination gear, and an actuator pivotally supporting said rack and having means whereby the same may be connected to a beam.

25 30 In testimony whereof I affix my signature.

ALEXANDER BOYNTON.
